LEG STUMP SOCK

John A. McCann, Burlington, N. J.

Application April 7, 1932, Serial No. 603,783

2 Claims. (Cl. 66—70)

This invention relates to the manufacture of stockings, and particularly to stockings for amputated legs, and known in the trade as leg stump socks.

5 The method of knitting involved in the present disclosure is applicable to tubular fabrics having a great variety of purposes, but is especially adaptable for stump socks because of the greater strength provided by the method disclosed herein, whereby the stump sock, which is subjected to great stress between the stump and the socket, is given a longer life.

10 The object of the invention is to provide an improved method of narrowing the stocking at the bottom or stump end of the same.

15 A further object of the invention is to provide an improved stump sock, and one which will have greater strength along the narrowing line of same.

20 According to the invention, the stump sock which is knit on a Lamb type machine, if knit upward, has the loop on the next to the last needle of each end of each bank transferred over the then extreme loop and onto the next 25 succeeding previously idle needle, and such operation occurring at every half course until the desired narrowing is attained.

If knit downward, the outer loop is transferred to the second needle at each half course.

25 The drawing illustrates an embodiment of the invention and the views therein are as follows:

Figure 1 is the side view of the stump sock, showing the narrowing point about which the invention is centered.

30 Figure 2 shows one bank of the needles of a Lamb type knitting machine.

Figure 3 shows a fragmentary enlarged view of the stitch formation, seen from the "wrong" side.

35 Figure 4 is a diagrammatic top plan of the needles and joint stitch at the bottom of the sock, and

Figure 5 is a similar view showing by the small circles the first regular or circular knitting 40 stitch in the tubular formation of the stocking.

When knitting in the usual manner the stump sock 6 is narrowed by having the outer stitch transferred inward one needle at a predetermined number of course, and the final narrowing 45 7 is preformed just before the tube or stocking is closed at the point 8.

The foregoing deals with the downward knitting of the stocking, that is from the top to the tip, but in some cases, and in fact most 50 cases, the stocking is knit from the bottom up,

that is to say, the set-up connecting stitches 8 are knit by the co-operation of both banks of needles in the Lamb type machine, and thereafter, the knitting continues in the usual manner alternately by the two banks of needles 9 and 11, to produce a circular knit. 5

In such case, the widening of the stocking will commence immediately after the set-up joining stitches 8 have been cast on.

Referring now to Figure 4, which shows the 10 set-up stitch on the needle banks 9 and 11, the machine is immediately changed so as to perform the regular circular knitting as shown in Figure 5.

It has always been the custom when widening, 15 to transfer the loop on the outer needle 12 to the adjacent idle needle 13 at the point A, then transfer the loop on the outer needle 14 to the next idle needle 15 at the point B, then perform the same operation at the point C and 20 then at the point D so that in every course of yarn, there will be a transferred widening stitch at each side of the stocking.

This universal method of widening makes a 25 weak point in the stocking by leaving larger open spaces where the yarn has been taken from the outer needle.

To overcome this objection, I take the loop cast off from the needle 16 at the point A and transfer it onto the idle needle 13, and the loop 30 cast off from the needle 17 at the point B, I transfer onto the idle needle 15. In like manner at the points C and D, I take the loops cast off from the needles 18 and 19 and transfer same into the needles 20 and 21, respectively. 35

Referring now to Figure 3, the ends indicated as 8 will be understood to be the initial or cast on stitches, as shown at Figure 4 of the drawings, and the stitches 22 the first circular or single ply knitting. 40

At this course the stitch cast off from the needle 16 will be manually drawn out, crossing over the stitch supported by the needle 12 and cast on to the needle 13, on the same bank of needles, which, up to that time, was an idle 45 needle.

One or more complete courses are then knitted, as indicated at 33. At the course 33 the stitch cast off from the needle 18 will be manually drawn out, as shown at 35, and cast on to the then idle needle 20, also on the same bank of needles. Another course 26 is then added and the stitch cast off from the needle 12 will be drawn out, as indicated at 28, and cast onto the 50 needle 38. Another course 29 being knitted, the 55

loop cast off from the needle 30 will be drawn out, as indicated at 31, and cast onto the needle 34. This will be continued until the desired width has been attained, each widening being 5 confined to its own bank of needles.

The widening may take place following any predetermined number of knitted courses, depending upon the abruptness of widening found desirable. The illustration at Figure 3 is not, 10 therefore, intended to govern in all cases, but is merely illustrative. It will be understood that Figure 3 is the view from the "wrong" side of the knitting, at one end of one bank of needles of the Lamb type machine, the original cast on 15 stitches 8 being indicated as cut apart and the dotted connecting lines indicating their original relation. This is necessary for the reason that showing the widening stitches for both banks of needles would otherwise show the stitches 8 only in end elevation. The corresponding end 20 of the opposite bank will, of course, be similarly treated, while the opposite ends of the banks will be likewise treated.

It will be understood, of course, that the widening by the drawing out of the stitches, as disclosed, will be effected alternately at opposite ends of the banks and at opposite banks at the opposite ends to give symmetry to the knitted article.

30 It will also be understood that Figure 3 is purely diagrammatic, and that the knitted article will not, in fact, have the appearance as at Figure 3, for the reason that the drawing out of the cast off stitches, as indicated at 35, 28 35 and 31, will distort the surrounding stitches, drawing them into a more compact relation whereby greater strength is attained at the line of widening.

Figure 2 illustrates the method of narrowing 40 in case the stocking is knitted downward, and in that case, the loop on the outer needle 23

will be transferred across the loop on the needle 24 to the hook of the needle 25 in the direction shown by the arrow.

By this method of widening or narrowing, I obtain a fabric which is considerably stronger 5 at the width changing point and one which will not have the large openings or holes inherent in the present methods of manufacturing this type of goods.

Of course, the stocking illustrated may be 10 modified in various ways without departing from the invention herein set forth and hereafter claimed.

The invention is hereby claimed as follows:

1. The method of widening during the production of fabric upon a knitting machine having parallel banks of needles, consisting in lifting the last loop cast off from one needle, second in line from the end of one bank of active needles, carrying said loop across a loop upon 20 the next adjacent needle at the end of that bank of needles, and casting it on to the next adjacent and theretofore idle needle in the same bank, as a new stitch.

2. The herein described method of widening 25 fabrics knitted on a Lamb type machine having two banks of needles comprising the steps of first, knitting the closing stitches, then knitting normally on the two banks of said machine alternately, then transferring the loop cast off from 30 the needle next to the end loop-holding needle of one bank to the adjacent idle needle, then knitting once across, then transferring the loop cast off from the next to the last loop-holding needle at the end of the bank, opposite the first 35 transfer to the first loopless needle of that bank, and then continuing such transfer at each half course until the desired width is attained always on the same bank of needles.

JOHN A. McCANN.
